THIRD RAIL SUPPORTING DEVICE

William C. Banks, Jersey City, N. J.

Application October 16, 1935, Serial No. 45,261

4 Claims. (Cl. 191—32)

This invention relates to the insulator supporting means which sustain the electric power conducting third-rail usually mounted to extend along and parallel to the track rails of electrically operated railway systems.

In the operation of such systems, a contact shoe normally extends from the motor car into spring pressed sliding contact with the power rail, and a pre-determined spacial and operating relationship exists between the two contacting elements which must be maintained to insure the supply of electric energy to the train.

This invention is concerned with the problem arising when a change made in the existing system results in a change of position or relative displacement of the contact shoe with respect to the power rail which upsets the required operating relationship of the contact elements. Consequently, it is one object of this invention to devise simple and efficient compensating means for rendering existing power rail supports, for instance, those disclosed in my Patent No. 1,837,096, granted Dec. 15, 1931, adaptable to such a condition of structural change; to make possible the re-location of the power rail; and more specifically, the using of higher or taller rails, all without necessitating discard of the existing component parts of the supports; without impairing their structural stability, or efficiency; and without disturbing the substantially permanently anchored main base element thereof. For this reason, the invention contemplates providing a height-increasing adaptor element as a compensating element or means to be incorporated in an existing rail support.

According to one feature, an auxiliary base or adaptor member is interposed between the conventional rail supporting insulator body and its original or main base element, and the position of this adaptor member is insured by its engaging relationship with the associated parts of the rail supporting structure in which it is incorporated. Other features relate to the specific shape of the adaptor member in view of its adaptation to an existing rail supporting arrangement.

The rail support disclosed in the above mentioned patent comprises a main base element having means for insuring thereon the position of a rail supporting insulating body. Normally, the base element is suitably anchored relative to the ground and has a rising stem which carries a rail protector which is spaced from and overlying the top of the power rail, and according to that patent the space between the top or con-

tact face of the power rail and the protector is made adjustable to meet the space requirements of the contact shoe which is to lodge and operate within that space.

In a preferred embodiment, an auxiliary base or adaptor member is inserted between the original or existing base element and the existing insulator body for the purpose of elevating the power rail upward a pre-determined distance, incidentally to suit an upward relocation of the contact shoe. Such change in elevation of the power rail can be seconded by a corresponding adjustment of the rail protector. The auxiliary base member interengages with the associated component elements of the rail support in such a manner that positive pre-determined positioning and bearing interrelationship of all parts of the combination is insured.

The invention possesses other objects and features of advantage, some of which, with the foregoing, will be set forth in the following description. In the accompanying drawing, for the purpose of example, there has been illustrated the best embodiment of the invention now known, but such embodiment is to be regarded as typical only of many possible embodiments and the invention is not to be limited thereto.

In the drawing:

Fig. 1 is a vertical section through a standard rail supporting and protector arrangement having the novel adaptor member incorporated therein.

Fig. 2 is a detailed section taken along line 2—2 upon Fig. 1, showing the interengagement of the adaptor member with the existing main base element.

Fig. 3 is a section taken along line 3—3 upon Fig. 1.

Fig. 4 is a detail perspective view of the adaptor element.

The rail supporting structure herein contemplated basically includes a main base element 10, which may be stamped out of flat material, formed with a flat bottom portion 11, a cylindrical portion or boss 12 rising therefrom, and a pair of marginal or peripheral upstanding flange portions 13 and 14. The base portion continues upwardly at one side thereof into a rising stem portion 15 upon which is to be adjustably sustained a rail protector 16 having a corresponding depending stem portion 17 which is shown to be adjustably mounted upon the rising stem portion 15 in the manner substantially described in the above mentioned Patent 1,837,096, as by means of bolt and nut connections 18 and 19 hold-

ing the two stem portions 15 and 17 together when holes 20 in both are registering and a hooked portion 21 of the depending stem portion engages in one of the holes 20 of the rising stem portion.

5 Anchoring bolts 22 and 23 are indicated to fasten the main base element 10 relative to the ground as upon a rail cross tie or other base as indicated at 24.

10 The main base element 10 is normally adapted to have positioned and seated thereon an insulator body 25 which in turn supports a power rail 26.

15 According to the present invention there is provided a hollow adaptor member or auxiliary base member 27 shaped to sustain and position the insulator body 25 thereon substantially the same as the main base element 10 is designed to do, but also adapted in turn itself to be positioned and seated upon the main base element 10. With this hollow adaptor member 27 interposed between the main base element 10 and the insulator body 25, the latter will be sustained in a pre-determined raised or relocated position.

20 25 It should be understood that in its relocated position the insulator body 25 need not necessarily register with the vertical center line of its original position, but that it is herein shown to be thus in registry in view of the fact that the contact shoe (not shown) should have been displaced in vertical direction only due to an increase in the height of the track rails.

Consequently, one preferred form as disclosed in Fig. 1 shows the hollow adaptor element 27 to be circular, and concentrically arranged with respect to the cylindrical protrusion or boss 12 of the main base element 10. Therefore, the adaptor element or auxiliary base member 27 comprises an annular substantially flat faced body portion 28 upon which is to engage a corresponding annular bottom face of the insulator body 25; and it comprises a rising cylindrical central reduced top portion or boss 29 of substantially the same dimension as the boss 12 of the main base element 10 to serve for positioning the insulator body by extending into the hollow or depression 29a thereof, and it finally includes a marginal or peripheral downwardly extending skirt portion 30 which in turn serves to position the adaptor member 27 relative to the main base element 10.

50 While the adaptor member 27 may thus be positioned by virtue of the concentric relation of the downwardly extending skirt portion 30 thereof with respect to the upwardly extending flange portions or ribs 13, 14, of the main base element 10, it should be understood that the protrusion or boss 12 may also serve as a centering means for the adaptor member 27 with respect to the central interior portion thereof.

60 In the practice of the invention and in assembling the new combination of elements, if it is to be assumed that in the existing installation of the power rail all parts of the original rail supporting structure and especially the height of the insulator body 25 had been designed to correspond to the pre-determined location of the contact shoe of the power driving car of the train, then a condition can arise as through increase of height of the track rails, which is identical with a displacement or dislocation of the contact shoe. So, in order to compensate according to this invention for such displacement, it is merely necessary to raise the power rail 26 and its supporting insulator body 25 from the main base element 10, and to

interpose between them the above described adaptor member 27.

It will be noted that the insertion between the standard parts, that is to say, between the insulator member 25 and the main base element 10, of the adaptor member 27 designed to interengage with these parts, will provide an auxiliary base for the insulator member and the rail, which as to mechanical security is equivalent to the original mounting of the insulator body in its primary base position directly upon the main base element 10. Moreover, inasmuch as the auxiliary base or adaptor member 27 is designed to simulate the effective contours of the original base, there is found no impairment of the insulating capacity of the insulator body 25.

Considered as an article of manufacture the auxiliary base member or adaptor member 27 is substantially of the configuration disclosed and capable of being inserted between and associated 20 with the standard parts of existing power rail installations for the purpose described and in the manner described.

Although the weight of the power rail can to a certain extent be relied upon to hold the component parts of the structure in their interrelated position, additional conventional ties may be provided to secure the assembly.

I claim:

1. In a power rail assembly, the combination 30 with a power rail, an insulator body upon which said rail rests and which insulator body has a depression arranged substantially centrally in the bottom thereof and in shape substantially corresponding to a boss hereinafter to 35 me mentioned, and a fixed main base element adapted to support said insulator body and said rail, said base element having upstanding marginal flange portions and a central rising substantially cylindrical boss adapted 40 to extend into and lodge in the depression of said insulator body, of a substantially hollow adaptor member interposed between said base element and said insulator body and thereby substantially enclosing said boss, 45 whereby to effect the re-location to a relatively raised position of said power rail, while sustaining said insulator member in spaced relation with the base element, which adaptor member comprises a substantially horizontal body portion upon which to sustain the corresponding bottom portion of the insulator body, a peripheral skirt portion extending down from said body portion and adapted to rest upon said base element and extending into a position-defining 50 relationship with said upstanding marginal flange portions, and also comprises a central cylindrical reduced top portion substantially corresponding to the shape of and extending into the depression of said insulator member, said skirt 55 portion being sufficiently high and substantially at least as high as said boss so as to insure the accommodation of said boss within the hollow of the adaptor member and relative to the central interior portion of said member.

2. In a power rail assembly, the combination 60 with a power rail, an insulator body upon which said rail rests and which insulator body has a depression arranged substantially centrally in the bottom thereof and in shape substantially corresponding to a boss hereinafter to be mentioned, and a fixed main base element adapted 65 to support said insulator body and said rail, said base element having a rising substantially cylindrical boss adapted to extend into and lodge 70

in the depression of said insulator body and thereby capable of positioning the insulator body relative to said base element, of a substantially hollow adaptor member interposed between said 5 base element and said insulator body and substantially enclosing said boss, whereby to effect the re-location to a relatively raised position of said power rail while sustaining said insulator member in spaced relation with the base 10 element, which adaptor member comprises a substantially horizontal body portion upon which to sustain the corresponding bottom portion of the insulator body, a peripheral skirt portion extending from said body portion and adapted to 15 rest upon said base element, and also comprises a central rising hollow cylindrical reduced top portion substantially corresponding to the inner contours of and extending into the depression of said insulator member, said boss extending 20 into substantially concentric and centering relationship with the interior contour of the bottom section of said top portion so as to define thereby the position of the adaptor member relative to said base element.

25 3. In a power rail assembly, the combination comprising a power rail, an insulator body upon which said rail rests and which insulator body has a depression arranged substantially centrally in the bottom thereof and substantially 30 corresponding to a boss hereinafter to be mentioned, a fixed main base element adapted to support said insulator body and said rail, said base element having a rising substantially cylindrical boss adapted to extend into and lodge 35 in the depression of said insulator body when the same is located in its primary base position directly upon said main base element, a substantially hollow adaptor member interposed between said base element and said insulator body 40 and thereby substantially enclosing said boss, whereby to effect the re-location to a relatively raised position of said power rail while sustaining said insulator member in spaced relation with said base element, which adaptor member comprises a relatively wide base portion adapted to 45 rest upon and to engage in predetermined position upon said base element and substantially

surrounding said boss, and further comprises a reduced cylindrical top portion substantially corresponding to the shape of an extending into the depression of said insulator member, said adaptor member thus being effective to interengage with said base element on the one hand and with the insulator body on the other hand so as to maintain and insure a predetermined interrelationship of said base element and said insulator body and which relationship is 10 substantially equivalent mechanically and electrically to the maintaining of the parts in said primary position.

4. In a power rail assembly, the combination comprising a power rail, an insulator body upon 15 which said rail rests and which insulator body has a depression substantially centrally in the bottom thereof and substantially corresponding to a boss hereinafter to be mentioned, a fixed main base element having a rising substantially 20 cylindrical boss adapted to extend into and lodge in the depression of said insulator body, a substantially hollow adaptor member interposed between said base element and said insulator thereby substantially occluding said boss and sus- 25 taining said insulator member in spaced relation with the base element, which adaptor member comprises a relatively wide base portion adapted to rest upon and to engage in predetermined position upon said base element and sub- 30 stantially surrounding said boss, and further a reduced top portion extending into and substantially corresponding to the inner contours of the depression in said insulator member, said adaptor member thus being effective to inter- 35 engage with said base element on the one hand and with the insulator body on the other hand, so as to maintain and insure a predetermined inter-relationship of said base element and said insulator body, a rail protector spaced from and 40 extending above and substantially parallel to said rail, and adjustable supporting means therefor, permitting adjustment of the rail protector in coordination with the relocation of the power rail as effected by said adaptor member. 45
